(57) **CLAIM**

I claim the ornamental design for a fishing and shrimping light, as shown and described.

DESCRIPTION

FIG. 1 is a perspective view of a fishing and shrimping light, showing a first embodiment of my new design;

FIG. 2 is a bottom plan view of FIG. 1;

FIG. 3 is a top plan view of FIG. 1;

FIG. 4 is a left-side elevational view of FIG. 1;

FIG. 5 is a right-side elevational view of FIG. 1;

FIG. 6 is a front elevational view of FIG. 1;

FIG. 7 is a rear elevational view of FIG. 1;

FIG. 8 is a perspective view of a second embodiment thereof;

FIG. 9 is a bottom plan view of FIG. 8;

FIG. 10 is a top plan view of FIG. 8;

FIG. 11 is a left-side elevational view of FIG. 8;

FIG. 12 is a right-side elevational view of FIG. 8;

FIG. 13 is a front elevational view of FIG. 8;

FIG. 14 is a rear elevational view of FIG. 8;

FIG. 15 is a perspective view of a third embodiment thereof;

FIG. 16 is a bottom plan view of FIG. 15;

FIG. 17 is a top plan view of FIG. 15;

FIG. 18 is a left-side elevational view of FIG. 15;

FIG. 19 is a right-side elevational view of FIG. 15;

FIG. 20 is a front elevational view of FIG. 15;

FIG. 21 is a rear elevational view of FIG. 15;

FIG. 22 is a perspective view of a fourth embodiment thereof;

FIG. 23 is a bottom plan view of FIG. 22;

FIG. 24 is a top plan view of FIG. 22;

FIG. 25 is a left-side elevational view of FIG. 22;

FIG. 26 is a right-side elevational view of FIG. 22;

FIG. 27 is a front elevational view of FIG. 22; and,

FIG. 28 is a rear elevational view of FIG. 22.

The Fishing and Shrimping Light is shown with a symbolic break in its length. The appearance of any portion of the article between the breaks forms no part of the claimed design. The broken lines show portions of the article which form no part of the claimed design.

1 Claim, 20 Drawing Sheets
